CLAIM

The ornamental design for a pilot valve for solenoid valve, as shown and described.

DESCRIPTION

FIG. 1 is a top and right front perspective view of a pilot valve for solenoid valve, showing our design;

FIG. 2 is a front elevational view thereof;

FIG. 3 is a right side elevational view thereof, the left side view being a mirror image of the side view shown;

FIG. 4 is a top plan view thereof;

FIG. 5 is a bottom plan view thereof;

FIG. 6 is a rear elevational view thereof; and,

FIG. 7 is a left side elevational view thereof when in use with a main valve and a lead wire.

The main valve and lead wire shown in FIG. 7 are shown in broken lines for illustrated purposes only and form no part of the claimed invention.
